(57) **CLAIM**

The ornamental design for a “tire”, as shown and described.

DESCRIPTION

FIG. 1 is a front view of a tire showing our design; FIG. 2 is a perspective view thereof;

FIG. 3 is a side view thereof, wherein the opposite side view is the same; and,

FIG. 4 is a fragmentary enlarged front view showing the details of the tread portion thereof.

1 Claim, 4 Drawing Sheets

FIG. 1

FIG. 2

FIG. 3

FIG. 4
